UNITED STATES PATENT OFFICE.

JACUB SCHWARTZMAN, OF BROOKLYN, NEW YORK.

WIRE FABRIC.

1,143,517.

Specification of Letters Patent. Patented July 6, 1915.

Application filed August 31, 1914. Serial No. 359,303.

To all whom it may concern:

Be it known that I, JACUB SCHWARTZMAN, a citizen of the United States, residing at Brooklyn, in the county of Queens and State of New York, have invented certain new and useful Improvements in Wire Fabric; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 The present invention has reference to a novel construction of wire fabric adapted, more particularly, for use as a flexible bed-bottom or springs, in connection with beds, couches and other furniture.

20 The present invention has for its principal object to provide a fabric of the kind indicated which is made up of an assemblage of novel longitudinally and laterally extending links co-operating together to produce a strong, durable and easily manufactured fabric. The said novel longitudinally and laterally extending links are coupled together in a novel manner so that the upper surface of the fabric formed thereby, and 25 upon which the mattress of a bed, or the like, is supported, presents a smooth surface without exposed wire ends to catch or tear the mattress. Furthermore, the arrangement and association of the laterally extending links with the longitudinally extending links is such that the former maintain the latter against undue lateral yielding toward one another, and serve to spread apart and maintain properly spaced from one another the longitudinal links, and yet do not interfere with or reduce the desired flexibility of the fabric as a whole.

30 A further object of the invention is to provide in a novel association and arrangement with the longitudinal marginal edges of the fabric a reinforcing or edge-stiffening strip or band.

35 Other objects of this invention not at this time more particularly enumerated will be clearly understood from the following detailed description of the present invention.

With the various objects of the present invention in view, the said invention consists, primarily, in the novel wire fabric hereinafter set forth; and, the invention

consists, furthermore, in the novel arrangements and combinations of the several devices and parts, as well as in the details of the construction of the same, all of which will be more fully described in the accompanying specification, and then finally embodied in the claims which are appended to and which form an essential part of this specification.

The invention is clearly illustrated in the accompanying drawings, in which:—

Figure 1 is a plan view of a portion of a wire fabric, illustrating one embodiment of the principles of the present invention; and Fig. 2 is a longitudinal section of the same, taken on line 2—2 in said Fig. 1 looking in the direction of the arrow x. Fig. 3 is a perspective view of one of the longitudinal links used in making said wire fabric; and Fig. 4 is a perspective view of one of the lateral links used in making said wire fabric. Fig. 5 is a plan view of a portion of a wire fabric also embodying the principles of the present invention, but illustrating a slightly modified form of and modified arrangement 80 or assembly of the longitudinal links used in making said wire fabric; Fig. 6 is a longitudinal section of the same, taken on line 6—6 in said Fig. 5, looking in the direction of the arrow y; and Fig. 7 is a perspective 85 view of said modified form of longitudinal link. Figs. 8 and 9 are respectively plan views of a portion of a wire fabric made of slightly modified forms of said novel longitudinal and lateral links, still embodying, 90 however, the principles of the present invention.

Similar characters of reference are employed in all of the above described views, to indicate corresponding parts.

Referring now to the form of wire fabric illustrated in Figs. 1 to 4 inclusive of the drawings the reference character 1 indicates the longitudinal links, each link being made of a length of wire doubled upon itself to 100 form a pair of longitudinally extending arms 2, the said arms 2 being formed adjacent to their connected ends with inwardly projecting bends or indentations 3, which, in combination with the connected ends or 105 doubled over portion of the link-body, provide a practically closed ring-shaped loop 4 at one end of the link-body. The free ends of each of said arms 2 of the link-body are turned or bent back upon themselves to 110

form eye-portions 5 disposed to extend in a plane at right angles to the general plane of the link-body.

The reference character 6 indicates the 5 main-body of the lateral links, each lateral link having at each end a downwardly extending arm 7 projecting substantially at right angles to said main body 6. Formed at the juncture of said main body 6 and its 10 arms 7 are upwardly extending rounded corner projections or U-shaped loops 8, the same providing seats for the eye-portions 5 of said longitudinal links when said lateral links are threaded therethrough in assembling the respective types of links together 15 to produce the complete fabric. The free ends of each arm 7 of the lateral link are turned or bent back upon themselves to form eye-portions 9 disposed to extend in 20 a plane at right angles to the general plane of the lateral link-bodies.

The longitudinal links, formed as above described are arranged in lateral rows, with their eye-portions 5 in lateral alinement. 25 When thus arranged the lateral links are assembled therewith, by threading a lateral link through the eye-portions 5 of adjacent arms 2 of a pair of adjoining longitudinal links so that said lateral link extends between and interconnects one of the arms 2 30 of one longitudinal link with an arm 2 of an adjoining longitudinal link throughout the width of the fabric. When thus assembled the eye-portions 5 seat themselves in the 35 respective corner projections or U-shaped loops 8 of the lateral links. As thus connected with the longitudinal links, the lateral links are so disposed with relation one to the other, that an arm 7 of one lateral link is brought in close proximity to and in alinement with an arm 7 of the adjoining lateral link, so that the respective eye-portions 9 of the adjoining arms 7 are alined 40 together and registered one with the other. 45 The next row of longitudinal links is now assembled and connected with the lateral links thus joined to the first row of longitudinal links, by threading a longitudinal link through the registered eye-portions 9 of adjoining arms 7 of said lateral links so that 50 the registered pair of eye-portions 9 seat themselves in the ring-shaped loop 4 at the upper or doubled end of said longitudinal links. Thus the alternate rows of inter-connected longitudinal and lateral links are 55 built up or connected one with the other until the desired length of wire fabric has been completed. To finish off the longitudinal edges of the fabric thus produced the 60 eye-portion 5 of the outer arm 2 of the outside longitudinal row of longitudinal links is connected with the ring-shaped loop of the longitudinal link next below the same by means of an interconnecting short link 65 10 having an eye-portion 11 at each end for

engaging the above mentioned portions of the longitudinally adjoining longitudinal links. It will thus be seen that when the respective rows of longitudinal and lateral links are assembled together in the manner above described, the former are in longitudinal alinement as well as lateral alinement, and all longitudinal strains upon the fabric are in the nature of a direct pull or strain, end to end, from one longitudinal 70 link to another, as transmitted through the interconnecting lateral links, and the latter not only serve to interconnect the longitudinal links so as to provide for a high degree of flexibility between the interconnected longitudinal links, but also serve as lateral stretchers between adjoining longitudinal links, whereby while the lateral flexibility of the wire fabric is retained in an efficient degree, the longitudinal links are, nevertheless, maintained spaced apart and separated laterally one from another, so that the moving together of longitudinal links toward one another, and a consequent uneven distribution of the strains throughout the area 80 of the wire fabric formed thereby, is prevented, and a smooth flexible supporting surface for the mattress is maintained. The ends of the fabric thus formed are connected by the usual helical springs 12 with the supporting frame-work of the bed or springs-frame. 85

In order to stiffen the longitudinal edges of the wire fabric thus formed, I provide a metallic band or strip 13, preferably of steel, 100 which is interwoven with the lateral links between the two outer longitudinal rows of longitudinal links. The ends of the stiffening band or strip 13 are perforated as at 14, and helical-springs 15 connect said strip 105 or band with the supporting frame-work of the bed or springs-frame. This arrangement is novel and useful in that the strip or band is directly inter-connected or interwoven with the longitudinal edges of the 110 wire fabric, and is maintained in the plane of said wire fabric in conformity with all the flexing movements of the latter by reason of such close interrelation of the same therewith. 115

Referring now to Figs. 5, 6 and 7 of the drawings I have illustrated a slightly modified form of wire fabric, still embodying, however, the principles of the present invention. In this construction the longitudinal links are modified slightly so that the same while arranged in horizontal rows are so disposed, when interconnected by the lateral links, that the longitudinal links of one row are in staggered relation to the longitudinal links of the adjoining lateral rows. To accomplish this end I employ a modified form of longitudinal link comprising a length of wire doubled upon itself to form a pair of longitudinally extending arms 16. 120 125 130 134

The upper portions of said arms 16 are inclined toward each other, thus providing inwardly inclined portions 17 converging toward the connected ends or doubled over portion of the link-body. The connected end or doubled over portion of the link-body is bowed or bent to form a practically closed ring-shaped loop 18 at one end of the link-body. The free ends of the arms 16 of the link-body are turned or bent back upon themselves to form eye-portions 19 disposed to extend in a plane at right angles to the general plane of the link-body. The form of lateral link employed in this modified construction of wire fabric is the same as that already above described, and therefore the same reference letters already employed above will serve to identify its construction.

The longitudinal links, formed as above described, are arranged in a laterally extending row, with their eye-portions 19 in lateral alinement. When thus arranged the lateral links are assembled therewith by threading a lateral link through the eye-portions 19 of the arms 16 of each longitudinal link, so that the arms 16 of the same longitudinal link are engaged by a lateral link, the eye-portions 19 of said arms 16 seating themselves in the respective corner projections or U-shaped loops 8 of said lateral link. In this manner there is a lateral link connected with the end of each longitudinal link. The next row of longitudinal links is now assembled and connected with the lateral links thus joined to the first row of longitudinal links, so that the eye-portions 9 of adjoining arms 7 of two adjacent lateral links seat themselves in the ring-shaped loop 18 at the upper or doubled end of said second row of longitudinal links, thus alining the said second row of longitudinal links in staggered relation to the longitudinal links of the first row, and so row upon row is thus joined together until the desired length of wire fabric is completed. As thus completed the arrangement of said lateral links in connection with said longitudinal links is such that the former maintain the latter in properly spaced relation one from the other so that the same are maintained against lateral displacement with relation to one another, and at the same time the high degree of flexibility of the fabric as a whole is not interfered with.

In both the first described construction of wire fabric, and in the immediately above described modification thereof, the ring-shaped loops 4 and 18, being practically closed, prevent the longitudinal and lateral links from collapsing together, or becoming disarranged before or while the same is being stretched in proper supported and suspended relation to the frame-work of the bed or springs-frame.

Referring now to Fig. 8 of the drawings I have illustrated a slightly modified construction of wire fabric in general character and arrangement, the same as that shown in Figs. 1 and 2 and above described, but in this modification the longitudinal links are formed of a length of wire doubled upon itself to provide the longitudinal arms 20, the doubled over portion forming the upper end of the same being formed to provide an angular projection 21 the apex 22 of which is rounded to form a seat-portion in which the eye-portions of the lateral links are engaged. The free ends of the arms 20 are provided with eye-portions 23. The lateral link employed in this construction comprises a main laterally extending body portion 24 having downwardly extending arms 25 slightly inclined outwardly, the free ends of said arms 25 having eye-portions 26, and corner projections or U-shaped-loops 27 being formed at the juncture of the said arms 25 with the body-portion 24 in which are seated and engaged the eye-portions 23 of the longitudinal links. The assembly of the longitudinal and lateral links thus formed is substantially the same as that described in connection with the construction of wire fabric shown in Figs. 1 and 2.

Referring now to Fig. 9 of the drawings I have illustrated still another modified construction of wire fabric in general character and arrangement the same as that shown in Figs. 5 and 6 of the accompanying drawings and above described, but in this construction the longitudinal links are formed of a wire doubled upon itself to provide longitudinal-arms 28 the upper portions of which are formed to provide inwardly inclined portions 29 which terminate at the doubled end of the link in a rounded portion 30 adapted to form a seat-portion in which the eye-portions of the lateral links are engaged. The free ends of the arms 28 are provided with eye-portions 31. The lateral link is of the same construction as already described in connection with the modification shown in Fig. 8 of the drawings, and the same reference characters will identify its detail parts. The assembly of the longitudinal and lateral links thus formed is substantially the same as that described in connection with the construction of wire fabric shown in Figs. 5 and 6.

I am aware that some changes may be made in the general arrangements and combinations of the several devices and parts, as well as in the details of the construction of the same, without departing from the scope of my present invention as set forth in the foregoing specification, and as defined in the claims which are appended thereto. Hence, I do not limit my present invention to the exact arrangements and combinations

of the several devices and parts, as described in the said specification, nor do I confine myself to the exact details of the construction of the said parts as illustrated in the accompanying drawings.

I claim:

1. A wire fabric comprising alternate transverse rows of longitudinal and lateral links, said longitudinal links each comprising a body doubled upon itself to provide a pair of longitudinal arms provided at their free ends with eye-portions, said lateral links each comprising a laterally extending body provided at each end with downwardly extending arms having eye-portions at their free ends, and U-shaped corner projections or loops formed at the juncture of said arms with said laterally extending body, the eye-portions of said longitudinal links being interconnected with and seated in said U-shaped corner projections or loops of said lateral links, and the eye-portions of said lateral links being interconnected with and seated in the doubled or closed ends of said longitudinal links.

2. A wire fabric comprising transverse rows of substantially U-shaped longitudinal links having eye-portions at their free ends, said rows of longitudinal links being interconnected with each other by lateral links having eye-portions at their ends and U-shaped loops adjacent to said eye-portions, said eye-portions of said longitudinal links being engaged in said U-shaped loops of said lateral links, and said eye-portions of said lateral links being engaged with the closed or doubled ends of said longitudinal links.

3. A wire fabric comprising transverse rows of substantially U-shaped longitudinal links having eye-portions at their free ends, said rows of longitudinal links being interconnected with each other by lateral links having eye-portions at their ends and U-shaped loops adjacent to said eye-portions, said eye-portions of said longitudinal links being engaged in said U-shaped loops of said lateral links, and said eye-portions of said lateral links being engaged with the closed or doubled ends of said longitudinal links, and flat reinforcing bands being interwoven over the lateral links between the two outer rows of longitudinal links at the longitudinal marginal edges of the wire fabric.

4. A wire fabric comprising alternate transverse rows of longitudinal and lateral links, said longitudinal links each comprising a body doubled upon itself to provide a pair of longitudinal arms having eye-portions at their free ends, said lateral links each comprising a laterally extending body provided at each end with arms projecting at substantially right angles thereto, said arms having eye-portions at their free ends,

and U-shaped corner-projections or loops formed at the juncture of said laterally extending body and its arms, the eye-portions of adjacent arms of adjoining longitudinal links being engaged respectively by said U-shaped corner projections or loops of a lateral link, and the eye-portions of adjacent arms of adjoining lateral links being engaged by the doubled or closed end of a longitudinal link in the next transverse row below.

5. A wire fabric comprising alternate transverse rows of longitudinal and lateral links, said longitudinal links each comprising a body doubled upon itself to provide a pair of longitudinal arms having eye-portions at their free ends, said lateral links each comprising a laterally extending body provided at each end with arms projecting at substantially right angles thereto, said arms having eye-portions at their free ends, and U-shaped corner-projections or loops formed at the juncture of said laterally extending body and its arms, the eye-portions of adjacent arms of adjoining longitudinal links being engaged respectively by said U-shaped corner projections or loops of a lateral link, and the eye-portions of adjacent arms of adjoining lateral links being engaged by the doubled or closed end of a longitudinal link in the next transverse row below, and flat reinforcing bands being interwoven over the lateral links between the two outer rows of longitudinal links at the longitudinal marginal edges of the wire fabric.

6. A wire fabric comprising alternate transverse rows of longitudinal and lateral links, said longitudinal links each comprising a body doubled upon itself to provide a pair of longitudinal arms having eye-portions at their free ends, said arms being squeezed together at their doubled over or connected ends to form a substantially closed ring-shaped loop, said lateral links each comprising a laterally extending body provided at each end with arms projecting at substantially right angles thereto, said arms having eye-portions at their free ends, and U-shaped corner-projections or loops formed at the juncture of said laterally extending body and its arms, the eye-portions of adjacent arms of adjoining longitudinal links being engaged respectively by said U-shaped corner-projections or loops of a lateral link, and the eye-portions of adjacent arms of adjoining lateral links being engaged by the ring-shaped loop of a longitudinal link in the next transverse row below.

7. A wire fabric comprising alternate transverse rows of longitudinal and lateral links, said longitudinal links each comprising a body doubled upon itself to provide a pair of longitudinal arms having eye-portions at their free ends, said arms being

squeezed together at their doubled over or connected ends to form a substantially closed ring-shaped loop, said lateral links each comprising a laterally extending body 5 provided at each end with arms projecting at substantially right angles thereto, said arms having eye-portions at their free ends, and U-shaped corner-projections or loops formed at the juncture of said laterally extending body and its arms, the eye-portions 10 of adjacent arms of adjoining longitudinal links being engaged respectively by said U-shaped corner-projections or loops of a lateral link, and the eye-portions of adjacent

arms of adjoining lateral links being engaged by the ring-shaped loop of a longitudinal link in the next transverse row below, and flat reinforcing bands being interwoven over the lateral links between the two outer rows of longitudinal links at the longitudinal marginal edges of the wire fabric. 15

In testimony, that I claim the invention set forth above I have hereunto set my hand this 28th day of August, 1914.

JACUB SCHWARTZMAN.
